UNITED STATES PATENT OFFICE.

ALEX BERNSTEIN, OF BOSTON, MASSACHUSETTS.

INCANDESCENT ELECTRIC LAMP.

SPECIFICATION forming part of Letters Patent No. 271,302, dated January 30, 1883.

Application filed November 4, 1882. (No model.)

To all whom it may concern:

Be it known that I, ALEX BERNSTEIN, of Boston, in the county of Suffolk and State of Massachusetts, have invented certain new and useful Improvements in Incandescent Electric Lamps, of which the following is a specification.

My invention relates to improvements in incandescent electric lamps, and has for its object the construction of an incandescent electric lamp which will be more durable than those heretofore in use, and more economical in the production of light by rendering the light-giving carbon capable of withstanding the action of strong currents and avoiding the disintegration which commonly takes place in carbon filaments. In order to obtain this desired effect, I make use of a hollow carbon cylinder as the light-giving part of the lamp, thereby obtaining an increased light-giving surface in proportion to the cross-section of the carbon. Although the use of such hollow cylinders has been proposed by others already, no lamp of this kind has ever been made to give practical results, because no proper means for constructing lamps of this kind had been devised. The success of lamps of this kind not only depends upon the way in which the carbon cylinder is made, but also upon its proper connection with the conducting-wires and the proper construction of those wires.

As my present invention refers especially to the construction of the lamp, I will not describe the manufacture of the carbon cylinders, but make that the subject of a separate application for Letters Patent.

My invention consists more especially of means for connecting the light-giving carbon cylinder with the conducting-wires, and also of means for allowing an expansion or contraction of the carbon cylinder without injury thereto. In the first instance intermediate socket-pieces of solid carbon are employed as carriers of the light-giving carbon. In the second instance the connection of one of the socket-pieces with one of the conducting-wires is made rigid, while the connection of the second socket with the other conducting-wire is made flexible. Further details of construction will be described hereinafter, and be pointed out in the claims.

In the accompanying drawings, in which

like letters refer to like parts, Figure 1 represents a vertical central section of my improved incandescent electric lamp. Figs. 2, 3, and 4 are horizontal sections, respectively, on lines ⁵⁵ *x x*, *y y*, and *z z* of Fig. 1.

A represents a hermetically-sealed evacuated glass globe of any approved shape or construction. Within the globe *A* a hollow carbon cylinder, *B*, is supported by solid carbon socket-pieces *C C'*, to which the carbon cylinder *B* is intimately applied by means of a suitable carbonaceous cement. The conducting-wires *E* and *F* pass through the base *A'* of the glass globe *A*, and are hermetically sealed ⁶⁵ thereto. The conducting-wire *F* is divided above the base *A'*, so as to form two branch wires, *f f*, which are supported, together with the conducting-wire *F*, by a glass button or stay, *e*. The ends of the conducting-wires *E* and *f f* are clamped by metallic sleeves *a a'* set into the ends of the socket-pieces *C C'*, and are intimately secured thereto by carbonaceous cement. The branch wires *f f* are applied to the clamping-sleeves at opposite ends of the ⁷⁰ socket-piece *C'*, while the wire *E* is applied to the lower end of the socket-piece *C*, as shown in Fig. 1. By the interposition of the socket-pieces *C C'* between the conducting-wires and the light-giving carbon cylinder the wires are ⁷⁵ protected against the direct heat of the incandescent carbon cylinder. As the conducting-wires and carbons are subject to unequal expansion during the passage of the current, means must be provided to prevent any strain ⁸⁰ on the light-giving carbon, which would result in its destruction. To provide against this, the conducting-wire *E* is constructed with a flexible portion, *b*, at its connection with socket-piece *C*, said flexible portion being formed of ⁸⁵ a number of thin wires. By means of the rigid connection of the branch wires *f f* with the socket-pieces *C'* and the flexible connection of the conducting-wire *E* with the socket-piece *C* provision is made for the expansion and ⁹⁰ contraction of the parts.

By means of the connections described and the larger surface of the light-giving part a stronger current of electricity may be sent through the carbon cylinder, and an increased ⁹⁵ amount of light produced without destroying the carbon cylinder, which latter is not ex-

posed to undue strains, so that the lamp is rendered more reliable, durable, and effective.

Having thus described my invention, I claim as new and desire to secure by Letters Patent—

- 5 1. In an incandescent electric lamp, the combination of a light-giving part formed of a hollow carbon cylinder, and solid carbon socket-pieces provided with metallic sleeves to which the conducting-wires are applied, substantially as shown and described.
- 10 2. In an incandescent electric lamp, the combination, with the conducting-wires, of solid carbon socket-pieces, and a hollow carbon cylinder interposed between them, one of said socket-pieces being rigidly connected to one of the conducting-wires, while the other is flexibly connected to the other conducting-wire, substantially as shown and described.
- 15 3. In an incandescent electric lamp, the combination of an air-tight glass globe, conducting-wires, carbon socket-pieces, a hollow carbon cylinder supported by the socket-pieces, to which the conducting-wires are applied, one of the conducting-wires being rigid, the other 20 conducting-wire flexible by being formed of a number of thin wires to provide for unequal expansion and contraction, as shown and described.
- 25 4. In an incandescent electric lamp, the combination of an air-tight glass globe, conducting-wires, carbon socket-pieces having metallic clamping-sleeves, to which the conducting-

wires are applied, and a hollow carbon cylinder supported by the carbon socket-pieces, one of which is rigidly, the other flexibly, connected 35 with the conducting-wires, substantially as shown and described.

5. In an incandescent electric lamp, the combination of an inclosing glass globe, conducting-wires, carbon socket-pieces having metallic clamping-sleeves for the conducting-wires, a hollow carbon cylinder supported by the carbon socket-pieces, one of which is rigidly, the other flexibly, connected to the conducting-wires, and a supporting glass button or 40 stay for the conducting-wires above the base of the lamp, substantially as set forth.

6. In an incandescent electric lamp, the combination of an air-tight glass globe, the conducting-wires which enter the neck of the 45 lamp, the branches of said wires which connect with the upper carbon socket-piece, the flexible group of wires connected with the lower carbon socket-piece, and the interposing hollow carbon cylinder, substantially as described.

In testimony that I claim the foregoing as my invention I have signed my name in presence of two subscribing witnesses.

ALEX BERNSTEIN.
